BABY FOOD JAR HOLDER

Lila M. Hanson and Bernard B. Hanson, Englewood, Colo., and George H. McCutcheon, Los Angeles, Calif., assignors to Westland Plastics, Inc., Newbury Park, Calif., a corporation of California

Filed July 31, 1967, Ser. No. 8,052

Term of patent 14 years

(Cl. D44—10)

FIG. 1.

FIG. 2.

FIG. 3.

FIG. 4.

FIG. 5.

FIG. 6.

FIG. 1 is an isometric view of a baby food jar holder showing our new design;

FIG. 2 is a side elevational view;

FIG. 3 is a top plan view;

FIG. 4 is a bottom plan view;

FIG. 5 is a front elevational view; and

FIG. 6 is a rear elevational view.

The spoon shown in broken lines in FIG. 1 is for illustrative purposes only.

We claim:

The ornamental design for a baby food jar holder, as shown and described.
